(57) **CLAIM**

The ornamental design for a spotting telescope support mount, as shown and described.

DESCRIPTION

FIG. 1 is a top elevational view of the Applicant's spotting telescope support mount.

FIG. 2 is a left side elevational view thereof.

FIG. 3 is a right side elevational view thereof.

FIG. 4 is a bottom elevational view thereof.

FIG. 5 is a front elevational view thereof.

FIG. 6 is a rear elevational view thereof; and,

FIG. 7 is a left side elevational view illustrating in broken lines a spotting scope mounted thereto, the broken lines depict environmental structure for illustrative purposes only and form no part of the claimed design.
